UNITED STATES PATENT OFFICE

HARVEY E. HERR, OF BUFFALO, NEW YORK, ASSIGNOR TO HERR MANUFACTURING CO., INC., OF BUFFALO, NEW YORK, A CORPORATION OF NEW YORK

SELF-LUBRICATING SPINNING RING

Application filed October 12, 1927. Serial No. 225,667.

This invention relates generally to lubricating means for spinning machines but more particularly to the lubrication of the rings of such machines on which the thread guides or travelers are mounted.

The principal object of the invention is the provision of a self-lubricating traverse ring of this character which automatically feeds the lubricant to the bearing surface of the ring in a thin film without liability of flooding and without danger of its lodging on the top surface of the ring and soiling or damaging the threads.

Another object is to provide the traverse ring with a built-in lubricating chamber constructed and organized to uniformly distribute the lubricant to the inner curved bearing surface of the ring and at a point below the top surface thereof.

A further object of the invention is to provide the ring with means for introducing the lubricant to its chamber.

In the accompanying drawings:—Figure 1 is a fragmentary sectional side view of a spinning machine showing the traverse or guide ring and associated parts. Figure 2 is an enlarged top plan view of the improved traverse ring with the traveler in position thereon. Figure 3 is an enlarged transverse section on line 3—3, Figure 2. Figure 4 is a fragmentary exaggerated section view similar to Figure 3. Figure 5 is a top plan view of the lower section of the traverse ring. Figure 6 is a fragmentary exaggerated transverse section of a slightly modified form of the invention.

Similar characters of reference indicate corresponding parts throughout the several views.

Referring now to Figure 1 showing a part of a spinning machine of ordinary construction, 10 indicates the take-up spool applied to the revolving spindle 11 driven by the belt 12 engaging the spool-pulley 13. In machines of this character, there is a set of feed rolls for the threads to be twisted and a take-up spool for each vertical row of supply bobbins and traversing the several take-up spools from end to end thereof is a vertically-reciprocating bar 14, each spool extending through

a corresponding opening 15 in the bar. Mounted on the top of the latter and surrounding the companion take-up spool 10 is a traverse ring 16 upon which the bar traveler 17 is adapted to revolve. During the operation of the machine, the bar traveler assumes a substantially upright position and revolves with and about the take-up spool, the threads passing under the traveler before being wound upon the spool, and the traverse bar 14 being reciprocated so that the threads are uniformly wound upon the spool in layers. As shown in Figures 2 and 3, the traverse ring 16 is removably seated on yieldable brackets 18 rising from a base-ring 19 suitably fastened to the reciprocating bar 14. The inner edge of the base-ring terminates in an upwardly-facing annular flange 20 which is spaced from the inner edge of the traverse ring to produce an annular channel 21 for receiving the depending legs of the bar traveler. The lower side of the traverse ring is spaced from the top of the base-ring 19 to produce a lateral continuation of the bar traveler receiving channel and such side 22 is slightly flared or beveled upwardly and outwardly, providing a bearing face for the bar traveler.

For the purpose of effectually lubricating the bar traveler, I make the traverse ring 16 of a hollow structure to provide a self-contained lubricant chamber 22, within its ordinary dimensional lines, having a restricted passage 23 at its inner edge or wall for supplying the necessary amount of lubricant to such inner edge and thence to the bar traveler, the lubricant flowing by gravity and aided by centrifugal force to the lower free ends of said traveler which engages the lower bearing face of the traverse ring. In the embodiment of the invention shown in Figures 1—5 inclusive, the ring is composed of a lower or base section 24 having an annular groove 25 which forms the body of the lubricant chamber, and an upper or cover section 26 which is shaped to extend over the grooved upper side of the base ring and around the outer side wall of the latter, such parts being united to constitute a unitary structure by a pressed fit or otherwise. The inner edge of the top

wall of the cover section 26 is preferably turned downwardly to form a flange 27 which produces a smooth, finished surface. The inner wall 28 of the grooved ring-section 24 is 5 preferably convexly curved at its inner edge and it slightly overlaps the flange 27 of the cover section in spaced relation to produce the restricted passage 23 for the emission or 10 delivery of the lubricant directly on to the curved face of said wall 28 and below the top wall of the cover section, as seen clearly in Figure 4. It will be observed in this figure that the top surface of the cover section 26 is slightly inclined downwardly and inwardly 15 and that the lubricant-passage 23 of the ring is below the level of the outer top side of the lubricant chamber 22, resulting in a gravity feed of the lubricant from said chamber through its restricted passage. However, 20 the head pressure on the lubricant is not sufficient to force it freely through the passage 23, due to the adhesion of the lubricant to the passage-walls, and the lubricant forms in a thin film or fillet at the meeting edges 25 of the ring parts 27, 28. As the traveler revolves about the traverse ring, it picks up sufficient oil to constantly and thoroughly lubricate the lower bearing surface of the ring, the oil flowing down the legs of the traveler 30 and thence outwardly by centrifugal force where it deposits a film of oil on said bearing surface.

In its top side the cover section 26 of the traverse ring has one or more vents 30 which 35 serve not only to eliminate the formation of air pockets in the lubricant-chamber 22 but also serve as inlets for introducing the lubricant thereto. These vents are preferably formed with rims or collars 31 projecting 40 above the surface of the ring-cover which act to avoid overflowing of the lubricant-chamber.

As shown in Figures 2, 3 and 4, the brackets 18 rising from the base ring 19 are located 45 outwardly of the periphery of the latter and are provided below their top edges with seats or ledges 32 preferably formed by slitting the brackets vertically and punching the resulting tongues inwardly. The outer bottom 50 side of the traverse ring engages the top edges of these tongues and by disposing the brackets and their seats as described, any possibility of the traveler bar legs striking these parts, as when the same assumes an abnormal 55 tilted position on the traverse ring, is effectually eliminated.

In the embodiment of the invention shown in Figure 6, the self-oiling traverse ring consists of a hollow body 33 formed and shaped 60 from a single blank of metal and its structural features are otherwise identical with those shown in Figures 1-5 inclusive.

Aside from its simplicity of construction and efficiency of operation, this self-oiling ring for bar travelers and the like insures

the introduction of the lubricant at a point directly on the inner bearing surface and remote from the top surface of the ring, whereby the lubricant is delivered where required without danger of its spreading onto the top 70 surface of the ring and soiling the threads being twisted.

I claim as my invention:

1. A device of the character described, comprising a hollow traverse ring adapted to contain a supply of lubricant, the inner wall of said ring having a circumferential upwardly-opening lubricant-conducting passage disposed between its top and bottom surfaces, the cross section of said ring being shaped 80 to cause the lubricant to be fed by gravity through said passage.

2. A device of the character described, comprising a traverse ring containing a lubricant chamber and having an inclined top 85 wall and a convexly curved inner wall terminating at its upper edge below the opposing inner edge of said top wall, and an upwardly-opening lubricant passage formed substantially at the meeting edges of said walls and 90 discharging at the upper edge of said inner wall and below the inner edge of said top wall.

3. A device of the character described, comprising a hollow traverse ring adapted to contain a supply of lubricant and an annular restricted lubricant discharge passage provided in the inner wall of the ring between its top and bottom walls, said passage opening 95 upwardly and the lubricant being discharged 100 onto said inner wall by the head-pressure of the lubricant contained in said ring.

4. A device of the character described, comprising a traverse ring containing a lubricant chamber, the top wall of said ring 105 sloping downwardly and inwardly, and a lubricant discharge passage formed in the inner wall of the ring below the level of the highest point of the ring chamber and below the top surface of said ring, whereby the lubricant 110 is fed by gravity from said chamber through its discharge passage.

5. A device of the character described, comprising a hollow traverse ring adapted to contain a supply of lubricant, the adjoining 115 edges of the top wall and inner wall of said ring being concentrically spaced to provide a restricted lubricant discharge passage, the upper edge of said inner wall terminating below the surface of said top wall and the outlet of the discharge passage being disposed at a point below the top surface of the ring, whereby the lubricant is fed by gravity 120 through its discharge opening.

6. A device of the character described, 125 comprising a hollow ring for receiving a lubricant and composed of a grooved base-section and a cover-section, the meeting ends of the inner wall of the base-section and the cover-section overlapping each other and

being laterally spaced to provide a restricted lubricant-discharge passage below the top surface of said cover-section.

7. A device of the character described, comprising a hollow ring for receiving a lubricant and composed of a grooved base-section and a cover-section, the inner wall of the base-section vertically overlapping the corresponding edge of the cover-section to form an upwardly-opening restricted lubricant discharge passage for delivering the lubricant below the surface of the cover-section and onto the inner wall of the base-section.

8. A device of the character described, comprising a hollow traverse ring containing a lubricant-chamber having a concentrically arranged lubricant discharge passage located substantially at the junction of the top wall and the inner wall of said ring, the inner wall projecting above the top of the adjoining portion of the lubricant-chamber and terminating below the surface of said top wall, whereby the lubricant is compelled to flow upwardly and be discharged from the chamber at a point below the surface of the traverse ring.

9. A device of the character described, comprising a hollow traverse ring containing a lubricant-chamber having a concentrically arranged lubricant discharge passage located substantially at the junction of the top wall and the inner wall of said ring, the top wall of said ring being inclined downwardly and inwardly to provide a gravity feed for the lubricant from its chamber through said discharge passage.

10. A device of the character described, comprising a hollow traverse ring containing a lubricant-chamber having a concentrically arranged lubricant discharge passage located substantially at the junction of the top wall and the inner wall of said ring, the top wall of said ring being inclined downwardly and inwardly to provide a gravity feed for the lubricant from its chamber through said discharge passage, the inner wall of the ring projecting above the adjoining portion of the lubricant-chamber and terminating below the surface of the top wall of the ring, whereby the lubricant is compelled to flow upwardly and be discharged from the chamber at a point below the surface of the traverse ring.

11. A device of the character described, comprising a hollow traverse ring for a bar traveler containing a lubricant-chamber and formed of an upper section and a lower section having oppositely-facing flanges at the inner peripheries thereof, said flanges being spaced apart in overlapping substantially vertical relation to provide a lubricant discharge passage.

12. A device of the character described, comprising a traverse ring containing a lubricant chamber, the top wall of said ring-chamber sloping downwardly and inwardly,

a lubricant discharge passage formed substantially at the junction of the top wall and the inner wall of said ring and having its outlet end disposed below the top surface of the ring and below the level of the highest point of the ring-chamber, whereby the lubricant is fed by gravity from the chamber through its discharge passage, and a combined vent and lubricant introducing opening formed in the top wall of the ring-chamber.
